WASHING MACHINE PUMP

Albert H. De Moss, Milwaukee, Wis.

Application January 27, 1951, Serial No. 208,166

2 Claims. (Cl. 103—103)

1

This invention relates to centrifugal pumps designed in such a way as to be especially applicable for pumping water and suds from washing machines and for other similar purposes.

An object of the invention is to provide a simple, economical and efficient pump for washing machines and for such other purposes.

Another object of the invention is to provide a pump for such purposes which can be manufactured by the employment of economical fabrication processes capable of being practiced by the use of inexpensive materials and equipment.

Another object of the invention is to provide a pump that easily may be installed on any kind of a standard washing machine and which may be installed without the necessity for providing supporting brackets, fixtures or devices that ordinarily are required in the installation of such pumps.

For a better understanding of the invention reference may now be had to the accompanying drawing forming a part of this specification in which:

Figure 1 is a longitudinal sectional view of a pump installed on an outlet or drain conduit leading from a washing machine or other similar device and which is illustrated as being connected to the drive shaft of the motor of the washing machine or device, the opposite end of the drive shaft being employed in driving the washing machine or device.

Figure 2 is a cross section through the conduit forming the inlet to the pump illustrated by Figure 1. Figure 2 is taken substantially in the plane of line 2—2 on Figure 1 and illustrates in end elevation and beyond the plane of line 2—2, the pump referred to as embracing the principles of the invention.

Figure 3 is a view similar to that illustrated by Figure 1 except that Figure 3 illustrates a slightly different form of pump embracing the principles of the invention.

Figure 4 is a cross sectional view of the structure illustrated by Figure 3. Figure 4 is taken substantially in the plane of line 4—4 on Figure 3 looking in the direction of the arrows thereon.

Referring particularly to Figures 1 and 2 it will be apparent that the numeral 10 indicates one end of an electric motor from which projects an axially disposed drive shaft indicated by the numeral 11. The opposite end of the motor 10 is employed in driving a washing machine or other similar device, through an extension of shaft 11 which projects from the motor in the opposite direction from the part shown.

2

The shaft 11 is adapted to drive a pump indicated generally at 12 which is employed for pumping suds and water from the outlet of the washing machine or other device. The pump 12 has an end wall 13 formed in such a way as to provide a concentrically disposed inlet connection 14 for the pump 12. The inlet connection 14 is adapted to be projected within a flexible rubber hose or outlet conduit 16 the opposite end of which is adapted to be secured to the outlet connection of the washing machine or other device with which the pump 10 is employed.

The pump 12 has a cylindrical casing 17 provided with a closed end 18 from which a bearing member 19 projects axially and outwardly with respect to the casing 17. The bearing member 19 contains a bushing 21 adapted to be press fitted or otherwise secured within the bearing member 19. The bushing 21 is adapted to receive a tubular pump shaft indicated at 22 which has an end projecting within the casing 17 and to which end a flexible rubber or other suitable impeller 23 is secured. The impeller 23 is adapted to be rotated by the shaft 22 in such manner that water and suds will be centrifugally impelled within the casing 17 from the inlet connection 14 to an outlet connection indicated by the numeral 24. The outlet connection 24 projects from the periphery of the casing 17 in the plane of rotation of the impeller 23 and with one side thereof disposed approximately in tangential relation to the interior cylindrical surface of the casing 17. A flexible rubber drain conduit or hose 25 is adapted to be connected to the outlet 24.

The motor shaft 11 is secured within the tubular pump shaft 22 by a tongue or key 26 which is adapted to engage a flat surface 27 formed on one side of the shaft 11. The key or tongue 26 is formed by cutting oppositely disposed and circumferentially extending slits 28 within an intermediate portion of the tubular shaft 22. The material of the tubular shaft 22 is then pressed inwardly between the slits 28 until the tongue 26 forms a cord or bar extending across the tube 22 between opposite ends of the slits 28. The tongue 26 is formed in such a way that the inner surface thereof engages the flat surface 27 formed on the shaft 11 to prevent relative rotation between the tubular shaft 22 and the motor shaft 11.

The inner end of the shaft 22 is adapted to extend a part of the way across the casing 17 toward the end wall 13. The inner end of the tubular shaft 22 is provided with diametrically opposed axially extending slots indicated at 29 which are adapted to aid in preventing rotation

of the impeller 23 with respect to the tubular shaft 22. The impeller 23 has a pair of oppositely disposed blades 31 and 32 and a hub 33, the latter being formed to project around and within the inner end of the tubular shaft 22. The surface of the hub 33 adjacent the tubular shaft 22 may be provided with an annular groove which is formed in such a way as to receive and to fit the inner end of the tubular shaft 22 and the diametrically opposed notches 29. The impeller 23 may be secured upon the inner end of the tubular shaft 22 by bonding or otherwise securing the rubber or other material of which the impeller is formed, to the engaging interior and exterior surfaces of the inner end of the tubular shaft 22. The hub 33 has an axially disposed portion indicated at 34 which projects within the inner end of the tubular shaft 22 and extends across the notches 29. A thrust or spacing ring 36 is disposed between the adjacent end surface of the hub 33 and the inner extremity of the bearing member 19. The bushing 21 terminates a short distance away from the adjacent surface of the thrust ring 36 in order to provide an annular space for receiving an annular sealing ring indicated at 37. The sealing ring may be formed of rubber of any kind or other suitable material and is compressed within the annular space referred to for the purpose of preventing leakage of liquid between the exterior surface of the tubular shaft 22 and the interior surface of the bushing 21. The end of the tubular shaft 22 adjacent the motor 10 is grooved in such a way as to receive a snap ring indicated at 48 which is adapted rotatably to engage a thrust washer 49 disposed between the snap ring 48 and the adjacent end surfaces of the bearing member 19 and the bushing 21.

The end wall 13 may be of frusto-conical shape as indicated by Figure 1 for the purpose of closely approaching the tapering ends of blades 31 and 32 of the impeller 23. The outer extremity of the wall 13 is formed in such a way as to provide an outwardly projecting peripheral flange which is indicated at 38 and the exterior surface of which is adapted to telescopically engage the interior surface of the cylindrical wall of the casing 17. The outer extremity of the flange 38 is flared outwardly to provide an annular bead indicated at 39 which is adapted to receive a rubber ring or gasket indicated at 41. The gasket 41 is compressed against the edge of the cylindrical outer wall of the casing 17 by an oppositely disposed pair of spring fasteners 42 which are pivoted on pins 43 between spaced lugs 44 projecting rearwardly from the outer periphery of the closed wall 18 of the casing 17. The fasteners 42 have hook shape ends 46 which are adapted resiliently to contract around the exterior surface of the bead 49 when the fasteners 42 are closed. The fasteners 42 compress the rings 41 for the purpose of sealing the casing 17 to prevent leakage of liquid between the adjacent surfaces of the casing and the end wall 13.

The pump 12 may be installed on a washing machine with which it is to be employed merely by projecting the tubular shaft 22 upon the end of the motor shaft 11 with the tongue 26 engaging the flat surface 27 of the shaft and by connecting the conduits 16 and 25 to the pump inlet 14 and outlet 24 respectively. The outlet or drain conduit 16 should be made in such a way as to be flexible enough to bend in any desired direction and to expand over the pump inlet 14 but sufficiently rigid so that it will not be distorted by

the reaction upon the casing 17 resulting from the rotation of the impeller 23.

The structure illustrated by the Figures 3 and 4 also comprises a cylindrical casing 51 having an end wall 52 and a bearing member 53, which is similar to the casing 17 in the structure disclosed by Figures 1 and 2. The bearing member 53 receives a bushing 54 in which is rotatably secured a tubular shaft 55 adapted to be driven by the motor shaft 11 through a tongue 56 projecting inwardly therefrom. The tongue 56 is formed in the tubular shaft 55 in the same manner that the tongue 26 is formed in the shaft 22 disclosed by Figures 1 and 2. The opposite end of the bearing member 53 is provided with thrust rings 57 and 58 and 59 which are respectively similar to the rings 37, 48 and 49 illustrated by the structure shown by Figures 1 and 2. An annular rubber sealing ring or other suitable sealing means indicated at 61 also is employed at the inner extremity of the bushing 54 for the purpose of preventing leakage between the inner surface of the bushing and the outer surface of the tubular shaft 55.

The inner extremity of the tubular shaft 55 supports an impeller 62 and the open end of the casing 51 is closed by an end wall 63 having a pump inlet connection 64 projecting axially therefrom. The impeller 62 is provided with blades 66 and 67 projecting in opposite directions from a centrally disposed hub indicated at 68. The hub 68 is of uniform diameter from one end to the other thereof and is of such size that the hub may be compressed within the interior surface of the end of the tubular shaft 55 projecting within and across the space within the casing 51. The tubular shaft 55 is provided with diametrically opposed and axially extending slots indicated at 71 for receiving the impeller blades 66 and 67 when the hub 68 is compressed within the end of the tubular shaft 55. The hub 68 and blades 66 and 67 may be made sufficiently large so that the compression thereof within the tubular shaft 55 and the slots 71 will provide a seal between the impeller 62 and the tubular shaft 55 thereby preventing leakage of liquid between the two. An additional seal may be provided for the interior surface of the tubular shaft 55. This may be constructed in a form of a curved disc indicated at 72 and the edges of which may be tightly compressed against the interior surface of the tubular shaft 55 by deforming the disc after it is inserted within the tubular shaft 55. The impeller 62 may be secured upon the end of the tubular shaft 55 by a snap ring indicated at 73.

The impeller 62 may be formed by cutting off suitable lengths from an extruded strip of rubber or other suitable material, such lengths being equal to the depth of one of the impellers 62.

The end wall 63 is provided with a suitable flange 74 and a bead 76 adapted to project within and over the casing 51 for compressing an annular rubber gasket indicated at 77. The end wall is held in position upon the casing 51 by fasteners 78 which are similar to the fasteners 42 illustrated in the structure shown by Figures 1 and 2. The casing 51 may be provided with a tangential outlet such as that indicated in the structure shown by Figures 1 and 2 or it may be provided with a radially disposed outlet such as that indicated by the numeral 79. The radially disposed outlet 79 will function practically as well as the tangentially disposed outlet 24 and the radially disposed outlet 79 has the advantage that a pump with

which it is employed may be used with motors driven in either direction. The outlet 79 is adapted to be connected to a hose or other suitable conduit 81 and through which the liquid delivered by the pump may be delivered to an elevated tub or to other liquid draining means. The inlet 64 is adapted to project within the end of drain conduit 82 which is similar to the drain conduit 16 shown by Figures 1 and 2.

The claims:

1. In a centrifugal pump, a tubular shaft having a plurality of axially extending slots projecting into said shaft from one end thereof, and a rotary liquid impeller of resilient material, said impeller having a hub, at least a portion of which snugly interfits within said slotted shaft end to seal said end and to provide readily detachable mounting of said impeller, said impeller having portions entering said slots to key said impeller to said shaft.

2. A readily demountable centrifugal pump comprising a cylindrical casing having a closed end and an open end, a tubular shaft projecting into said casing through a restricted opening in said closed end, said shaft having a plurality of axially extending slots projecting into said shaft from the end thereof within said casing, a rotary liquid impeller of resilient material, said impeller having a hub, at least a portion of which snugly interfits within said slotted shaft end to seal said end and to provide readily detachable mounting of said impeller, said impeller having portions entering said slots to key said impeller to said shaft, an end closure for said open end of said casing, said end closure being formed to provide

a peripheral flange adapted telescopically to engage the interior surface of said casing, said flange being formed beyond the adjacent end of said casing to provide an outwardly projecting annular bead having an inwardly disposed channel formed therein in opposed relation to the adjacent end of said casing, a resilient ring disposed in said channel between said casing end and said bead, and spring fastener means secured to the opposite end of said casing and having hooks formed at the ends thereof adjacent said bead for resiliently engaging said bead for compressing said ring and for securing said end closure in position upon said casing.
